HAIR WAVING DEVICE

Freda Mae Smysor, near Cozaddale, Ohio

Application January 11, 1937, Serial No. 119,893

6 Claims. (Cl. 132—38)

This invention relates to improvements in hair waving devices. The devices to which the present improvements are directed are designed for home use for the purpose of enabling the girl or 5 woman to produce waves in the hair the same as obtained by finger waving. In making a finger wave, the hair is shampooed and when completely wet with a wave set lotion applied is pushed into waved position by means of the fingers, and 10 thereafter held temporarily, while the hair dries, by means of hair pins, combs or like devices, permitting the hair to dry or set in a waved condition.

The present concept resides in the determination 15 that a jaw of a waving device can function separately as a hair holding means, fitting the contour of the head and functioning to hold the hair in position while another jaw, also fitting the contour of the head, may be placed across 20 the hair and moved relative to the first element for creating a swirl or flat wave and thereafter clipped to the first jaw for holding the wave while it dries. If desired, the jaws may be spaced when 25 the swirl is created and thereafter moved up to the first jaw and clipped thereto for creating a raised wave in addition to a swirl, the elements cooperating for efficiently holding the formed swirl or wave while it is setting or drying. The 30 jaw elements of this device are usable in either instance as combs.

It is the object of the present invention to provide 35 a hair waving device which is adjustable, fitting the contour of the head at any point, and which will set the hair perfectly flat on the head in the same manner as heretofore accomplished by finger waving, or which will create a raised wave of any width desired.

It is a further object of the invention to provide 40 hair waving devices which can be placed end to end around the head, and in rows, for making continuous waves without interference with each other.

It is a further object of the invention to provide 45 hair waving devices of this character which do not require the use of a comb for the purpose of moving the hair to a waved position, which provides cooperating parts enabling the person making the wave to move the hair to a waved position, and to thereafter by application of a cooperating 50 part to clamp the hair in the position to which it has been moved.

It is a further object to provide an improved 55 waving device which has the advantage that it does not require complete wetting of the hair, but merely damping, for the wavers hold each

wave firmly in place as it is made, the result being that one wave is not disarranged while another is being made as happens so often when finger waving is being done.

Other objects and further advantages will be 5 more fully apparent from a description of the accompanying drawings, in which:

Figure 1 is a side elevation of one jaw of the waving device.

Figure 2 is an enlarged sectional view taken on 10 line 2—2, Figure 1.

Figure 3 is a side elevation of the jaw of Figure 1.

Figure 4 is an enlarged sectional view taken on line 4—4, Figure 3, detailing the structure of the 15 jaw at its point of articulation.

Figure 5 is a side view of the other jaw of the waving device.

Figure 6 is a top plan view thereof.

Figure 7 is a sectional view taken on line 7—7, 20 Figure 5, illustrating the point of articulation of the jaw illustrated in Figure 5.

Figure 8 is a sectional view taken on line 8—8, 25 Figure 5, illustrating the ventilating apertures.

Figure 9 is a perspective view of a head showing 30 the application of the devices to the hair.

Figure 10 is a top plan view of the jaws of the device showing the intermediate stage of the operation of creating a wave, that is, one jaw moved in parallel spaced relation relative to the other. 35

Referring to the drawings, the separable sections or jaws of the waving device are indicated at 10 and 11 respectively. Each of these jaws or sections is articulated in the same manner. Each is arcuate consisting of sections 12 and 13 connected together at their adjacent ends by means of loosely secured rivets 14.

An overhanging and downturned flange portion 15 on one section of each jaw is formed adjacent the articulation overhanging the other section in 40 each case and forming a stop limiting articulating movement of the sections away from the head. Each jaw incorporates teeth 16 along its inner edge, these teeth inclined laterally from the plane of the jaw in each instance, and arranged so that when placed even, face to face, the teeth are directly opposite. When the jaws are brought together in setting a wave, the teeth of one jaw are disposed in the spaces between the teeth of the other jaw.

Each jaw includes gripping tangs 17 struck out 45 from the body of the jaw, one in each section of each jaw at right angles thereto, enabling the operator to swing the sections readily and to hold the jaw in position on the head. One of the 50

jaws, namely 11, is of double metal thickness so as to provide stability and rigidity to the assembled unit. In the case of this jaw 11, the teeth are struck out from the body of the metal projecting as described, whereas the teeth of jaw 10 are struck out from the edge, and the lower edge margin of the metal beyond the teeth as indicated at 19 is bent at an angle reverse to that of the teeth. Accordingly, when this jaw is placed against the head, it has two lines of contact, that is, along the ends of the teeth, as indicated at 20, and along the end of the flange, as indicated at 21. This stabilizes the jaw as placed on the head for movement in relation to the first jaw.

15 This latter jaw 11, being heavier, includes clips 22 for fastening the jaws together as they are brought into abutment with the hair secured therebetween. The clips consist of plate members pivotally attached to the respective sections 20 of the jaw by pivot pins 23 and providing U-shaped portions, best shown in Figure 2, of yieldable form, straddling the respective jaws. Upturned flanges 24 on the ends of these clips enable convenient lifting of the clips from position 25 for permitting separation of the jaws.

As shown in Figure 9, the first jaw, that is, jaw 10, is initially placed against the hair and head at the point at which the wave is desired. Due to the articulation of the element it conveniently adjusts to the particular contour of the head at that point. The operator is able to hold this jaw in position by means of the thumb and forefinger engaging the finger-hold flanges 17. This jaw holds the hair in position and takes the place of the second finger of the left hand as used in giving a finger wave. The second jaw is then placed about a quarter or a half inch away from or below, and directly opposite, the first jaw.

40 This second jaw may be likened to the conventional comb. Due to its articulation, it fits the contour of the head. As a result of its two lines of contact its position is stabilized and there is less tendency to rock.

45 This element 11 is then shifted or moved parallel to the fixed jaw 10 giving the hair a swirl or wave, and is then pushed up to the first jaw, whereupon the clips are set for fastening the two jaws together. In initially placing the second jaw prior to shifting, it is placed so that it will be exactly opposite the first jaw, with the teeth of the respective jaws adjacent, so that when shifted and moved up to the first jaw, the teeth will mesh and it will extend past the first jaw. 50 55 It will be appreciated that the raise of the wave is determined by the spacing of the jaws in the original position and the bunching of the hair. By placing the jaws very close together and then shifting one relative to the other, a swirl can be obtained which will lie perfectly flat against the head.

The wavers are placed in rows around the head as illustrated, that is, they are placed end to end without interference with each other. In making 60 a continuous wave around the head, the wavers are placed end to end, the lower waver, or jaw 11, being shifted in the opposite direction for

each row of waves. The jaw 11 will overlap the jaw 10 of the adjacent waving device so that the jaws are substantially in end to end abutment.

The wavers provide a quick easy practical and efficient means for waving the hair, the wave being automatically made by shifting and joining the jaws of the waver which thereafter holds the hair in position for setting or drying after the wave is created. The hair does not have to be completely wet as in regular finger waving which takes longer to dry, but need only be dampened, for the waving devices hold each wave firmly in position as it is made. For this reason one wave is not disturbed while making another, as happens when a person finger waves the hair. Of course, as is usual in waving, any style or arrangement of wave can be procured, depending upon the position in which the wavers are placed on the hair.

Having described my invention, I claim:

1. A waving device for forming and holding hair waves in position, comprising, a pair of independent jaw elements, each of which is arcuate and provides teeth along its curved inner side for engagement with the hair, and one of which provides clips for attaching the jaws together when they are brought together face to face.

2. A hair waving device, consisting of, entirely separable jaw members, said jaw members of arcuate form and articulated for adjustment to the contour of the head, each jaw providing teeth along its inner edge for engagement with the hair, finger-hold portions formed on each jaw for manipulating the same, and clips formed on one jaw adapted to engage over the other jaw when the jaws are placed face to face for securing the same together and upon the hair.

3. A hair waving device, consisting of, separable jaw elements adapted to engage across the hair and to be shifted relative to each other, and means for securing the jaws together when brought together face to face.

4. A device for waving hair, comprising, articulated jaws adapted to engage the hair and adaptable to the contour of the head of the person whose hair is being waved, said jaws detachable for movement in any manner relative to each other, and attachment devices for securing the jaws together when a wave has been created for holding the wave until set.

5. A hair waving device, consisting of entirely independently movable jaw members, said members of arcuate form and articulated for adjustment to the contour of the head, each jaw providing teeth along its inner edge for engagement with the hair, finger-hold portions formed on each jaw for manipulating the same, and clips adapted to secure the jaws together face to face and upon the hair.

6. A hair waving device, consisting of, jaw elements of arcuate form adapted to engage across the hair and articulated for fitting the contour of the head, said jaws shiftable relative to each other in any direction, and devices for securing the jaws together when disposed in face to face abutment.

FREDA MAE SMYSOR.
